Jacob E. A. Karpovsky

UNITED STATES PATENT OFFICE.

KARL STROSENREUTER, OF BROOKLYN, NEW YORK, ASSIGNOR TO ROSS HUNTER, OF ATLANTA, GEORGIA.

CUFF BUTTON.

Application filed March 11, 1922. Serial No. 542,819.

To all whom it may concern:

Be it known that I, KARL STROSENREUTER, a citizen of Germany, and resident of Brooklyn, in the county of Kings and State 5 of New York, have invented certain new and useful Improvements in Cuff Buttons, of which the following is a specification.

This invention relates to cuff buttons. The object of the invention is to provide a cuff 10 button comprising two buttons connected by an elastic member whereby to make the buttons self adjustable with respect to the cuffs and whereby the two parts of the cuff will be kept close together.

15 I am aware that broadly speaking it has been attempted to provide a cuff button of the character set forth, but the construction of such buttons has been rather expensive and to my knowledge such buttons have 20 not been a success.

In order to provide a generally improved button of the character set forth, I propose 25 to use two buttons of suitable size and form and connect them by means of an elastic member in such a manner that they may be manufactured in large quantities at little 30 cost.

I propose to use a plain round elastic member covered by a suitable spun layer of suitable 35 thread, for instance silk. The ends of the elastic are fastened within the button parts in such a manner that the latter are free to assume any position with respect to each other, the elastic and the cuff.

35 In the drawing illustrating this invention Figure 1 is a view of a cuff button embodying my invention, the button being shown very much enlarged and with parts in section.

40 Figure 2 is a face view of the button in natural size.

Referring to the drawing the cuff button comprises two buttons 3, 3 joined by an elastic member 4.

45 The elastic member preferably consists of a round elastic 5 having a suitable fabric or thread or spun covering 6.

50 Each button consists of two parts. A face portion or outer half 7 and a back portion 8. Each portion is made of preferably thin metal. The outer or face portion may be ornamented as may be desired.

The two portions of the button are joined by placing the back inside or within the

face portion and then seaming or pressing 55 the two parts together in a suitable die.

To this end the inner or back 8 is provided with an inner annular flange 9 which merges into two stepped annular portions 10 and 11, which latter is formed with an opening 12 surrounded by an inturned flange 13.

The face portion 7 is provided with an ornamental face 14 and an outer annular flange 15 adapted to be squeezed or crimped in over and to grip the inner flange 9 afore- 60 said.

In assembling the parts the end 16 of the elastic is passed through the opening 12 and lies between the two halves of the button, the back 8 being placed within the face 7. 70

Thereafter the two halves are forced together in a press and die (not shown) in such a manner that the end of the elastic is caught and pinched between the two halves of the button, which at the same time are 75 pressed together.

By reason of the fact that the elastic is thicker than the space between the two halves of the button, the elastic is caught firmly within the button and cannot come 80 out without wrecking the button.

The bulging ornamental face 14 strengthens the button, and the stepped or ridged back is similarly very much strengthened. Finally, the two adjacent flanges 9 and 15 85 grip each other firmly as shown.

The foregoing is thought to clearly set forth my invention, which, while shown in its preferred form, nevertheless is susceptible of changes in the detailed construction without departing from the principle of the invention and the scope of the appended 90 claims.

I claim:—

1. As a new article of manufacture, a 95 cuff button comprising two buttons joined by an elastic member, each of said buttons consisting of a back portion and a face portion, the back portion having an opening through which the end of the said elastic 100 passes so as to lie within the button between the two parts thereof, the said two button parts being adapted to be forced together to form a button and to grip the end of the elastic between them, substantially as 105 described.

2. As a new article of manufacture, a cuff button comprising two buttons and an elastic

member, each of said buttons consisting of a back portion and a face portion, the said back portion having an inner annular flange, said face portion having a cooperating outer annular flange, said back portion having an opening in the center through which the end of the said elastic member passes to join the said two buttons, the parts being so arranged

that the ends of the elastic member lie within each of the said buttons, the two parts of 10 which are adapted to be forced together with the said flanges adjacent to each other in locked position, the said two parts firmly gripping the said elastic member between them.

KARL STROSSENREUTER.
